UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

HEELING-MACHINE.

1,139,199.

Specification of Letters Patent. Patented May 11, 1915.

Application filed May 10, 1910. Serial No. 560,440.

To all whom it may concern:

Be it known that I, THOMAS LUND, a citizen of the United States, residing at Beverly, in the county of Essex and State of

5 Massachusetts, have invented certain Improvements in Heeling-Machines, of which the following description, in connection with the accompanying drawings, is a specification, like reference characters on 10 the drawings indicating like parts in the several figures.

The present invention relates to an improvement in band clamps adapted to engage the counter of a shoe while the heel 15 is being operated upon.

Automatic machines for performing operations upon the heel of a shoe after the outsole has been applied such, for instance, as nailing, trimming or breasting, are generally provided with a clamp to engage the counter of the shoe and properly position the shoe relative to the operating tools while the operation is being performed. Such a clamp is generally of flexible material formed as a U-shaped band to encircle the quarter part of the shoe and arranged to closely engage the upper just above the outsole. It is important that the band clamp be constructed so as to hold the shoe 10 firmly and rigidly in working position but also be adjustable to accommodate varying sizes and styles of shoes.

The objects of the present invention are to reorganize and improve the construction 15 of band clamps for heel machines of the character referred to. The features of the invention relate, therefore, to certain combinations and arrangements of parts, hereinafter described and claimed, which possess advantages in construction which will 20 be apparent to those skilled in the art.

The preferred embodiment of the invention is illustrated in the accompanying drawings, in which—

25 Figure 1 is a perspective of the band clamp, as a whole, detached from the machine in which it is to be used; Fig. 2 is a side elevation of the detached band clamp showing in dotted lines a variation from the 30 normal horizontal position of the clamp;

Fig. 3 is a detail, in section, through the central rear portion of the band support; and Fig. 4 is a diagrammatic view showing the action of the clamp in closing.

The embodiment of the invention illustrated in the drawings is similar in its general arrangement to the band clamp shown in United States Letters Patent to C. W. Glidden for a heel nailing machine, No. 500,486, dated June 27, 1893. In the present invention, as in the band clamp shown in that patent, there is provided a slide arranged for vertical movement on the machine, at the lower end of which is carried a band clamp support, within which the flexible U-shaped band is located, and to which it is connected by means of side links pivoted to the support and to ears on the band.

In the present invention a much stronger and simpler flexible band 2 is provided in that when it is stamped out it is provided with integral ears 3 at its upper edge which may be bent back at an angle to the body of the band to form the lugs to which the inner ends of the links are pivoted. It has been found that in the earlier form of band clamp, wherein the side links are connected to lugs riveted on the band, the strain upon the rivets is such that they are frequently broken. This earlier form of connection between the band and links is, therefore, unserviceable. With the present construction of integral lugs on the band this disadvantage has been entirely overcome.

In the band clamp illustrated in the patent hereinbefore referred to, no provision is made for adjusting the width of the clamp to accommodate varying widths of shoes to be operated upon in the machine. In the present invention such an adjustment is provided for by forming the support for the clamp in two parts 5 and 6, mounting them for transverse sliding movement in a T-shaped slot 7 in the front face of a carrier 8, and threading through the rear portions of said supports a right and left screw 9 which is held from axial movement by providing it with collars 10 at the outer and inner side of a lug, or flange, 12 at one

end of the carrier. The links 4 are pivoted at their inner ends to the lugs 3 by means of removable pins and at their outer ends to the forward ends of the supports 5 and 6 by similar removable pins all of which pins may be held in place by split pins or equivalent retaining means. The lug 3 at the rear end of the band clamp has removably pinned thereto a block 13 which carries a 10 rearwardly extending guide rod, or finger, 14 (Fig. 3) passing through an aperture in the carrier 8 formed for its reception. This block and finger is similar to that shown in the patent to Glidden hereinbefore referred to. With this construction the band clamp 2 may be opened or closed, for varying widths of shoes, by turning the threaded rod 9 in one direction or another. The right and left threads will cause the two parts 15 5 and 6 of the band clamp carrier to be separated or drawn together equally and simultaneously.

As will readily be understood, the mounting of the band is such that with the band 25 forward (see dotted lines in Fig. 4) as the supports 5 and 6 are drawn together in order to accommodate the band clamp to the narrower shoes, the supporting links 4 will be moved forward thereby drawing the 30 clamp forward and with it the rod 14 through its aperture in the carrier 8. The direction of movement of the band is reversed if the supports are moved apart. After a proper adjustment of the band 35 clamp, the shoe is placed in working position by forcing the band back between its supports until the block 13 is seated against the stationary carrier 8. As is well known to those skilled in the art, in positioning a 40 shoe in a machine for any operation upon the heel, the shoe must be placed in a definite and predetermined position relative to the operating tools. In varying sizes of shoes the size or location of the tools will 45 vary and, therefore, the working position of the shoe will have to be altered more or less. The device of the present invention is, therefore, provided with an adjustable stop for the block 13 to seat itself against when the 50 band 2 is moved backward within its supports during the positioning of a shoe in the machine. This stop may conveniently 55 comprise a sleeve 15 threaded into the band clamp carrier and through which the rod 14 projects, the sleeve carrying at its forward end a nut 16 by which it may be adjusted and which forms a stop against which the block 13 may abut. By adjusting the sleeve 15 toward and from the carrier 8, the rear- 60 ward, or operative, position of the band clamp, to accord with the size of the shoe being operated upon, is determined.

It is desirable that the shoe be held firmly against movement while being operated

upon and to gain this end the counter of the 65 shoe should be clasped tightly by the band. Referring now more particularly to Fig. 4, it is seen that when the band 2 is in the full line, or rearward, position, its width at the oppositely disposed links 4 is much less than 70 when in its dotted line, or forward, position. This is due to the use of rigid links, having no provision for loose play, for connecting the band to its support. When a shoe is removed from the machine, the band is pulled 75 out and is left in the dotted line position, Fig. 4. Thereafter, when adjusted by means of the screw 9 the opening is left somewhat greater than the width of the shoe to be operated upon. As the band is 80 moved backward between the arms of its support, however, the angular movement of the rigid links, which being mounted for pivotal movement only, acts to force the arms of the band inward against the shoe 85 counter causing the shoe to be tightly clamped when in operative position. The position of the stop nut 16 is such that the backward, or inward, movement of the band carries the links a little past dead center 90 (see Fig. 4). This permits a slight expansion of the band during the latter portion of its inward movement which operates to hold the band firmly seated within its supports with the shoe in operative position. The 95 band, while in this position, cannot move forward without some force being applied to bring the links past dead center again.

To hold the shoe to the best advantage, it should be clasped by a pressure on the 100 band throughout its depth. In the construction of the prior patent hereinbefore referred to, any pressure exerted against the sides of the clamp is transmitted through the small lugs by which the links are 105 connected to the band clamp. The pressure is, therefore, transmitted through the upper marginal portion of the clamp only and its lower marginal portion, owing to the fact that it is made of spring material, frequently does not engage the counter of the shoe at all being held somewhat away from the counter. To overcome this difficulty and provide a band clamp of flexible material which will engage the counter of the 110 shoe firmly throughout its entire depth, the inner ends of the links 4 and the block 13 are each provided with a depending portion 115 forming pressure blocks. These blocks have such a bearing against the clamp that 120 the pressure is transmitted to the shoe throughout the depth of the clamp. Such a construction provides for an even pressure upon the clamp both at its top and bottom and serves successfully to conform the 125 clamp to the counter of the shoe and hold the shoe firmly in the machine.

The heels of many shoes are provided with

a wedge lift which in the finished shoe causes the plane of the heel seat of the shoe to extend at a slight angle to the plane of the tread face of the heel. When this type 5 of heel is being attached, or otherwise operated upon in a heelng machine, the shoe should be held with the plane of its heel seat at the angle relative to the heel which it will assume in a completed shoe. To enable the 10 shoe conveniently to be so held, heretofore the band clamp has been mounted upon its support so that it can be tilted in a fore and aft direction and thus cause the clamp to be directed downwardly at the angle at 15 which the shoe should be held. Such an arrangement is illustrated in the prior patent referred to but in that patent the pivotal point is located substantially midway between the front and rear ends of the clamp. 20 With such a construction, as will be readily understood, when the clamp is tilted the relative position of the rear end of the clamp and the operating tools is different from the relative position of these parts when the 25 clamp is in its normal or horizontal position. This is disadvantageous for, as hereinbefore stated, it is highly desirable that when the shoe is moved backward into the machine it be to a definite point relative to the operating tools. To overcome this difficulty and 30 improve the band clamp so that the working position of any particular shoe in the machine is always the same, no matter to what angle the clamp may be tilted, provision has 35 been made in the present device for tilting the clamp about itself, preferably about the point *c* (Figs. 2 and 3) as a center. To accomplish this result, the carrier 8 is provided with two rearwardly extending ears 40 18, each of which is grooved at its inner side and curved to conform to a curved guide 19, extending from the lower end of the vertical sliding support 20 upon which the band clamp as a whole is sustained. The curve of 45 the guide 19 is determined by arcs of circles struck from the point *c* as a center. The carrier 8 may be held in any position of adjustment on the guide 19 by means of a set screw 21. With the construction just de- 50 scribed, by loosening the set screw 21 the band clamp carrier 8 may be tilted about itself to any desired angle from the horizontal and relocked in such position and such a tilting movement will not vary the 55 position of the rear of the clamp relative to the working tools. This is clearly illustrated in Fig. 2.

From the description heretofore given of the improved band clamp, it will be seen 60 that it possesses distinct advantages over band clamps of the prior art in that it not only may be adjusted for width but that an equal adjustment at each side of the band is obtained by means of a single adjusting de-

vice. Further advantages consist in the ad- 65 justments permitting shoes of varying sizes and styles to be properly positioned in the machine for the operation of the tools and permitting an independent adjustment for the proper positioning in the machine of 70 shoes provided with wedge heels. The device is still further advantageous in that it not only provides for a clamping pressure upon the counter of the shoe, enabling the shoe to unfailingly be securely and rigidly 75 held in operative position, but further in providing for a transmission of the pressure throughout the depth of the band.

The nature and scope of the present invention having been indicated and the preferred embodiment of the invention having been specifically described, what is claimed as new, is:—

1. In a device of the class described, po- 85 sitioning means for a shoe including a flexi- 90 ble clamping band, oppositely disposed sup- 95 porting members adjustable in a straight line toward and from each other, and piv- 100 oted links interposed between the band and the members.

2. In a device of the class described, the combination of a U-shaped band supported at three separate points by pressure blocks extending substantially the entire width of the band and adjusting mechanism con- 95 structed and arranged for adjusting two of the pressure blocks simultaneously toward or from each other in a right line.

3. A band clamp for heel machines, hav- 100 ing, in combination, a flexible U-shaped 105 band, a support therefor arranged outside the band, and links connecting the support and band, said links having heads rigid therewith at their inner ends extending sub- 110 stantially from one edge to the other of the band.

4. In a band clamp for heel machines, a flexible band having at one edge integral ears bent at an angle to the body of the band, a band support, and links pivotally 110 connected to said ears and to said support, the ends of said links which are connected to said ears being provided with pressure blocks extending substantially the entire width of the band.

5. In a band clamp for heel machines, the combination of a band support, a band sus- 115 tained thereby, and a segmental guide for said support, said guide having its center of curvature at the rear end of the band.

6. In a band clamp for heel machines, the combination of a band support, a band sus- 120 tained thereby, and a segmental guide ar- ranged to permit angular movement of said support in a vertical plane about a center at the rear end of the band.

7. A band clamp for heel machines, hav- 125 ing, in combination, a band support having

a flexible U-shaped band sustained thereby,
a single means for adjusting the arms of
the band toward and from each other for
varying widths of shoe, and means permit-
ting said band and its adjusting means to
be tilted about a horizontal axis passing
through a point *c* at the rear end of the band.

In testimony whereof I have signed my
name to this specification in the presence of
two subscribing witnesses.

THOMAS LUND.
